UNITED STATES PATENT OFFICE

WALTER SCHÄFFER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

ARRANGEMENT FOR AUDIO FREQUENCY AMPLIFICATION

Application filed September 29, 1923, Serial No. 665,525, and in Germany October 13, 1922.

The present invention relates to an improved arrangement for audio frequency amplification. It comprises vacuum tubes arranged in cascade and has the important advantage that only the first and last transformers of the arrangement are iron core transformers, the vacuum tubes being coupled to each other by high frequency transformers. The amplification can, of course, be increased by using additional vacuum tubes. Regardless of the number of tubes used, however, the arrangement need contain only two iron core transformers, one in the grid circuit of the first tube and the other in the plate or output circuit of the last tube. A large number of amplifiers arranged in accordance with the invention can be connected in series without causing howling due to back-coupling.

In the drawing, Fig. 1 is a diagrammatic representation of a circuit arrangement embodying the invention; and

Fig. 2 is a diagrammatic representation of a circuit arrangement of modified form also embodying the invention.

In the arrangement represented in Fig. 1 a vacuum tube generator 10 which operates at any high frequency wave is combined with a similar vacuum tube generator 12 which, however, preferably produces a high frequency wave of a frequency different from that of the wave produced by the generator 10. The audio frequency currents to be amplified are impressed upon the grid of the first generator tube 10 by an iron core transformer 14, and the amplified audio frequency may be delivered to a line 16 coupled to the plate circuit of the generator tube 12 by a second iron core transformer 18. In the use of the arrangement, the high frequency generated by the tube 10 is modulated by the audio frequency currents and directed by the radio frequency transformer into the grid circuit of the tube 12, and the modulated high frequency in the output circuit of the tube 12 at the end of the cascade arrangement of tubes is then rectified and detected by any suitable means (not shown).

Instead of taking off energy from oscillator tube 12 by means of transformer 18, a

coupling may be made to the inductance 30 of oscillating circuit 30, 31 by means of coupling coil 32 leading to a suitable detector means.

It has been found that audio frequency currents may be amplified by an arrangement according to the invention through any desired range, since the tubes in the above-mentioned cascade can be used in any quantity without danger of causing howling, which is usually noticed when a considerable number of amplifying tubes are arranged in the usual manner. Applicant believes that his invention makes possible for the first time the construction of a low frequency amplifier without using any intermediate iron core transformers, and a further advantage of the invention results from the ability to use high frequency transformers for coupling together the tubes of the arrangement, since the iron core transformers employed in known low frequency amplifiers for coupling the plate circuits of the tubes of the arrangement to the grids of succeeding tubes cause very considerable losses in efficiency due to the resistances in the primary and secondary windings of the transformers, as well as hysteresis and eddy currents in the cores of the transformers. Applicant has also found that the elimination of iron core transformers from between the tubes of an arrangement for amplifying audio frequencies causes it to have increased selectivity.

Fig. 2 shows special means for increasing the co-efficient of amplification. In the use of the arrangement shown in this figure, not only the grid voltage which is to be amplified, but also a variable plate voltage which supports the amplification is supplied to the second vacuum tube 12. This aim is achieved by connecting the energy-source 22 of the second vacuum tube 12 in series with the secondary winding 24 of a transformer 25, the primary 26 of which is inserted in the direct current plate circuit of the tube 10, whereby the voltage of the current supply circuit of the second vacuum tube 12 is increased or decreased in accordance with the variations of the voltage in the plate circuit of the tube 10. When more than two tubes are included

in the arrangement, a transformer secondary 24 can, of course, be used for each of the tubes following the first one.

Having described my invention, what I claim is:

- 5 1. An arrangement for audio frequency amplification comprising a source of audio frequency currents, a plurality of vacuum tube generators of high frequency energy, an iron core transformer for coupling one of the generators to said source of audio frequency currents, a delivery circuit for the amplified audio frequency currents, and means for coupling the output circuit of the last of said generators to said delivery circuit, and radio frequency transformers for coupling the generators together in cascade relation.
- 10 2. An arrangement for audio frequency amplification comprising vacuum tube generators of high frequency energy, said generators being similarly coupled together and one of them operating to produce high frequency energy of a frequency different from that of the energy produced by another of the generators, an iron core transformer for impressing audio frequency currents upon the grid circuit of the first of the generators to cause the high frequency energy produced thereby to be modulated in accordance with said low frequency currents, and means in the output circuit of the last of the generators for delivering the amplified audio frequency currents from the arrangement.
- 15 3. An arrangement for audio frequency amplification comprising vacuum tube generators of high frequency energy, each of said generators after the first operating to produce high frequency energy of a frequency different from that of the energy produced by the preceding generator, an iron core transformer for impressing audio frequency currents upon the grid circuit of the first of the generators to cause the high frequency energy produced thereby to be modulated in accordance with said low frequency currents, and means in the output circuit of the last of the generators for delivering the amplified audio frequency currents from the arrangement and radio frequency transformers for coupling the generators together in cascade relation.
- 20 4. An arrangement for audio frequency amplification comprising a vacuum tube generator of high frequency current, a second vacuum tube generator of high frequency current having its input circuit coupled with the output circuit of the first generator, means for coupling the plate circuit of the second generator to the plate circuit of the first generator and means for impressing the audio frequency currents to be amplified upon the grid circuit of the first generator.
- 25 5. An arrangement for amplifying audio frequency currents comprising a vacuum tube generator of high frequency energy, a second

vacuum tube generator of high frequency energy having its input circuit coupled with the output circuit of the first generator, a source of energy in the plate circuit of said second generator and a transformer having its secondary winding arranged in series with said source of energy and having its primary winding arranged in the plate circuit of the first generator for causing the voltage of the second generator to be increased or decreased in accordance with variations in the voltage in the plate circuit of the first generator.
